[57] **CLAIM**

The ornamental design for a hinged door handle assembly, as shown and described.

DESCRIPTION

FIG. 1 is a front perspective view of a hinged door handle assembly;

FIG. 2 is a rear perspective view thereof;

FIG. 3 is an enlarged front elevational view thereof;

FIG. 4 is a rear elevational view thereof;

FIG. 5 is a right side elevational view thereof;

FIG. 6 is a left side elevational view thereof;

FIG. 7 is a top plan view thereof; and,

FIG. 8 is a bottom plan view thereof.

The broken line showings of a portion of a door in FIGS. 1, 2, 5, 6, 7 and 8 are for illustrative purposes only and form no part of the claimed design.
